UNITED STATES PATENT OFFICE

157,760

INSULATING BODY FOR AN ELECTRIC CAPACITOR

Eric James Hiles, Whitton, England, assignor to
United Insulator Company Limited, Tolworth,
Surbiton, England, a British company

Application May 20, 1949, Serial No. 2,789
In Great Britain March 9, 1949

Term of patent 14 years

(Cl. D26—10)

To all whom it may concern:

Be it known that I, Eric James Hiles, a citizen subject of the King of Great Britain, residing at Whitton, Middlesex, England, have invented a new, original, and ornamental Design for an Insulating Body for an Electric Capacitor, of which the following is a specification, reference being had to the accompanying drawings, forming a part thereof.

Figure 1 is a perspective view of an insulating body for an electric capacitor, showing my new design;

Figure 2 is a front view; and

Figure 3 is an end view thereof.

I claim:

The ornamental design for an insulating body for an electric capacitor, as shown.

ERIC JAMES HILES.
